UNITED STATES PATENT OFFICE.

IVORY W. HARLOW, OF PLYMOUTH, MASSACHUSETTS.

TEA-KETTLE.

SPECIFICATION forming part of Letters Patent No. 298,465, dated May 13, 1884.

Application filed September 14, 1883. (No model.)

To all whom it may concern:

Be it known that I, IVORY W. HARLOW, of 5
Plymouth, in the county of Plymouth and State
of Massachusetts, a citizen of the United States,
have invented certain new and useful Improve-
ments in Tea-Kettles, of which the following
is a full, clear, and exact description, refer-
ence being had to the accompanying drawings
in explaining its nature, in which—
10 Figure 1 is a vertical section of a tea-kettle
having my improvement. Fig. 2 is a cross-
section of the upper part of the kettle and
cover, and Fig. 3 is a plan view thereof.

The invention relates to a tea-kettle having
15 a bail attached to the cover, and to means for
locking the cover, when closed, to the kettle,
and for removing it therefrom, as hereinafter
specified.

Referring to the drawings, A is the body of
20 the tea-kettle.

B is the cover. It has cast upon its under
surface the circular projection or stop b, which,
when the cover is closed, is adapted to come
in contact with the inner surface, b', of the
25 wall about the opening to the kettle. The
cover also has the tongue or latch C, which
shuts into the notch or catch e, cast in or at-
tached to the body of the kettle. The cover
also has the latch D, which preferably is of the
30 shape represented in Fig. 2. It is pivoted at
d to lugs d', projecting upwardly from the cov-
er, and has the upwardly-extending portion d'',
which serves as a push-lever, and which may
have upon it a wood or other knob of non-con-
35 ducting material. This bent arm or latch has
a limited movement upon its pivot, so that up-
on the closing of the cover the outer end, d³,
falls or shuts into the opening of the kettle im-
mediately adjacent to the inner side, d⁴, of the
40 wall about the kettle-opening. The extent of
this movement is limited by the stop d⁵, which
comes in contact with the upper surface of the
kettle-cover. There may be cast on the under
surface of the cover the guiding-lugs d⁶—one on
45 each side of the latch-arm D—to keep it cen-
tered. The cover is pivoted at E to swing lat-
erally.

F is the bail. It preferably has the handle
f, and is rigidly attached to the cover B, the
50 ends of the bail being inserted through holes
in the cover and riveted upon the under

surface, and curved outwardly immediately
above the cover, as represented, and prefera-
bly within notches formed in the projections
f' upon the upper surface of the cover. It 55
will be seen that by this construction when the
kettle-cover closes the kettle-opening it is so
located that it cannot be moved in either direc-
tion, and is held firmly to the kettle by the
tongue or latch C, and that as the handle and 60
bail are rigidly secured to the cover the tea-
kettle can be easily moved and tipped without
moving the cover. It will also be seen that, as
the handle is attached to the cover, upon the
movement of the cover laterally it is moved 65
out of the way with it, and that therefore it
answers not only for lifting the tea-kettle, but
also for the handle of the cover as well.

In order that the kettle-opening may be used
for holding pots, kettles, &c., I have made the 70
cover entirely removable from the kettle; and
this I accomplish by forming the pivot e as
shown in Fig. 1—that is, its lower portion has
a locking-extension, e', and the pivot-hole e² is
formed substantially as shown in plan in Fig. 3. 75
In removing and placing the cover the locking-
projection is brought in line with the portion
e' of the pivot-hole and moved vertically until
it has cleared the wall of the kettle, when the
cover can be turned and will be locked to the 80
kettle. A stop, e⁵, projecting downwardly
from the inner surface of the wall next the
pivot-hole extension e', serves to prevent the
locking-projection upon the pivot from being
turned beyond the hole, so that the cover can 85
be easily removed by bringing the locking-pro-
jection up against the stop, and then moving
the cover upwardly. The portion of the wall
of the kettle about the pivot-hole is made level.
To open the kettle it is simply necessary to 90
move the locking-latch D upwardly by means
of its projecting arm d² and slide the cover
horizontally on the pivot E. Of course any
other suitable device for locking the cover se-
curely to the kettle may be employed without 95
departing from the spirit of the invention.

The invention is applicable to all other
classes of kettles other than tea-kettles to
which it can be attached.

Among the advantages of this construction 100
may be mentioned these: The bail is always up-
right, and being rigidly attached to the cover,

when the cover is locked perfect control of the kettle is assured. There is no danger from scalding by steam in opening the cover. The cover being removable and the catch *c* not projecting above the kettle-opening, the kettle may be used for supporting steamers or dishes of proper shape to fit into opening or rest upon the wall surrounding it.

I am aware of Patent Reissue No. 4,006, granted E. G. Littlefield, May 31, 1870, and Patent No. 64,685, granted A. N. Merrill, dated May 14, 1867; but as the first-named patent does not describe a cover provided with a bail or any means of locking the cover in place, and as the last-named patent does not describe a removable cover or an automatic latch or catch similar to that described herein, I consider that they do not contain the features of my invention.

Having thus fully described my invention, I claim and desire to secure by Letters Patent of the United States—

1. The combination of the cover B, pivoted at *e* to the kettle-body A, having a tongue, C, stop *b*, and the locking-latch *D*, shaped and arranged in relation to the cover as specified,

with the kettle-body A, having the catch *c*, all substantially as and for the purposes described.

2. The cover B, having the downward-projecting stop or lug *b*, cast therewith, and the latch *D*, pivoted at *d* to the cover, to have an automatic oscillating movement in relation thereto, all substantially as and for the purposes set forth.

3. The combination of the kettle A, having the pivot-hole *e*² *e*⁴, shaped as described, and stop *e*⁵, with the kettle-cover B, having the pivot *e*, with a locking-projection, *e'*, all substantially as and for the purposes described.

4. The combination of the cover B, pivoted to the body of the kettle, and having the downwardly-projecting tongue C, with the catch *c*, all substantially as and for the purposes described.

5. The combination of the cover B and lever *D*, pivoted to the cover, as described, and having the stop *d*⁵, with the body A, all substantially as and for the purposes described.

IVORY W. HARLOW.
